UNITED STATES PATENT OFFICE.

CARL E. M. MILLER, OF NEW YORK, N. Y.

INCLINE-TRUCK.

933,321.

Specification of Letters Patent.

Patented Sept. 7, 1909.

Application filed February 11, 1909. Serial No. 477,365.

To all whom it may concern:

Be it known that I, CARL E. M. MILLER, of the city, county, and State of New York, have invented a new and useful Improvement 5 in Incline-Trucks, of which the following is a full, clear, and exact description.

My invention relates to improvements in trucks, and more especially to hand trucks such as are used around stores, docks, and 10 other places to haul materials from one point to another. My invention is not, however, limited to any special size.

In places where much material is handled, often a great many trucks are necessary, and 15 the material, in the form of bundles of paper, bales of stuff, bags, etc., are piled on the trucks and then taken from the trucks and piled on benches or other places.

The object of my invention is to produce 20 a truck which will obviate the necessity of so much handling, which can be slipped under the bench or under an article to be moved, if the latter stands on legs or stands up from the ground, and which can be readily operated so as to lift the bench or thing 25 from the ground or floor so that it can be hauled to the desired point, and then easily set down.

My invention is intended to produce an inclined plane and screw operated mechanism 30 by which the lifting can be done by a single operator, so that economy in time and labor is effected.

My invention is further intended to produce 35 an article of this character which is simple and inexpensive, and which can in fact be made for about the cost of an ordinary truck.

Reference is to be had to the accompanying 40 drawings forming a part of this specification, in which similar reference characters indicate corresponding parts in all the views.

Figure 1 is a side elevation of my improved truck, showing its application to a 45 bench. Fig. 2 is a longitudinal section of the truck. Fig. 3 is a cross section of the truck, and Fig. 4 is a front end view thereof.

The truck is provided with a two-part 50 body portion 10 and 11, which are made of wedge shape and oppositely tapered so that one may ride on the other, and for convenience these structures are made hollow with the bottom of the part 10 closed and with 55 the top of the part 11 likewise closed. So long as a suitable top and bottom are pro-

vided, however, it matters little whether the parts are closed at top and bottom or not. For convenience the lower member of the body 10 has a front 10^a raised somewhat in 60 the center, and the front end of the upper member 11 is left open so that the said member can slide forward over the part 10^a when adjusted as hereinafter described. The two parts are placed together with the thin part 65 of one member opposite the thick part of the other, as shown in Fig. 1, and for convenience the lower member 10 is mounted on suitable rollers or casters 12 and has perforated lugs 13 which can be engaged by a 70 suitable handle 14 when the truck is to be hauled from place to place.

In order that the two truck members 10 and 11 may maintain the proper relation and may slip readily longitudinally with relation to each other, one, preferably the lower member, is provided with a dovetail grooved strip 15 on its upper longitudinal edges, and the upper member is provided with strips 16 having tongues 17 to fit in the grooves of the 80 strip 15. This prevents lateral displacement and makes a simple connection which permits the parts to slide easily, especially if the meeting parts are oiled, but obviously any usual form of ball or other bearing can 85 be provided to make the parts slip more readily.

The adjustment of the member 11 on the member 10 is effected by means of the screw 18 which is arranged longitudinally in the 90 member 10 and turns at its front end in a suitable bearing plate 20 on the front 10^a of the lower member, but if the lower member should be metal instead of wood, of course the bearing plate would be unnecessary. 95 The screw has its front end squared as shown at 19 so that the wrench 19^a can be easily applied to it. The screw engages a nut 21 which is fixed in a transverse depending hanger 23 on the inner part of the member 100 11, and to further brace the parts, the hanger 23 has metal plates 22 on both sides, which are secured to the hanger and to the flanges of the nuts 21. The hanger 23 can be further supported by braces 24 connecting it 105 with the top of the member 11.

The apparatus is used as follows. We will suppose that a bench 25 which is provided with legs 26, has stuff piled on it, and is to be moved. In this case the screw 18 is 110 turned by means of the wrench 19^a so as to make the truck low enough to permit it to

be pushed under the bench 25, after which the screw is reversed and the member 11 moved up on the member 10 so that it lifts the bench off its feet and it can then be 5 hauled to the desired place. In connection with this method of moving, it will be noticed that I provide a button 27 near the top edge and back side of the member 11, which can be turned up so as to engage the bench 10 or other thing on the truck and prevent it from slipping off.

Obviously this truck can be made of any desired height so that it can be pushed beneath ordinary benches and other articles, 15 and it will be seen that any loose thing under which it can be placed, can be easily raised and transported. For instance, we will assume that the bench 25 has material piled up on it which is to be moved. In 20 this case instead of piling the material in small quantities on the truck and then moving it and re-piling it, the bench and the material thereon can be transported at one operation.

25 It will be seen that this truck can be built strong enough so that it may be pushed under automobiles and operated to raise them so as to lift the weight from the tires, thus saving the latter. The trucks can also be 30 used conveniently in connection with rail-

roads for unloading freight, and for many other purposes.

Having thus fully described my invention, I claim as new and desire to secure by Letters Patent:—

35

1. In a truck, a body portion composed of two members, the lower member having inclined ways on the upper part thereof, the upper member having a flat top and a lower surface inclined to meet the top surface of 40 the lower member, a screw mechanism for adjusting the two members, the screw of said mechanism being parallel with the top surface of the lower member.

2. In a truck, a body portion composed of 45 two members, the lower member having an inclined top surface, the upper member having a lower surface meeting and corresponding to the inclined top surface of the lower member, a fixed nut supported rigidly by a 50 hanger within one of the said members and at right angles with the inclined surface, and a rotatable screw journaled on the other member and lying parallel with said inclined surface and engaging the fixed nut.
